UNITED STATES PATENT OFFICE

THOMAS E. REID, OF CONCORD, NORTH CAROLINA, ASSIGNOR TO DRAPER CORPORATION, OF HOPEDALE, MASSACHUSETTS, A CORPORATION OF MAINE

DRIVING-ROD CONNECTION FOR LOOM LET-OFF MECHANISM

Application filed October 23, 1928. Serial No. 314,445.

This invention relates to a let-off mechanism for looms and particularly to the actuating mechanism therefor.

A let-off mechanism has for its purpose the control of the rotation of a warp beam in the loom so as to let off under even tension the warps from the beam during and, as required by, the weaving operation. The controlling mechanism is usually operated by connection 5 to the lay rocker shaft so that during each cycle of movement of the lay a predetermined amount of warps is let off.

In a familiar type of let-off mechanism, a rocker arm is secured to the lay rock shaft 15 and connected by a driving rod to a pallet or pawl carrying lever which controls the operation of the let-off mechanism. A lost motion connection is necessary between the rocker arm and the driving rod. The usual connection 20 at this point consists of a stud cast on the rocker arm and a longitudinally slotted casting on the driving rod cooperating therewith. As these parts are seldom, if ever, lubricated and are not carefully finished, a great deal of 25 wear takes place between the casting and the stud interfering with the proper operation of the mechanism and necessitating frequent replacement of the main portion of the rocker arm, of a casting on the driving rod, or of 30 both.

The object of the invention is primarily to provide a simple and efficient form of connection between the rocker arm and the driving rod which will operate for long periods 35 of time without substantial wear, without necessity of replacement of parts and without requiring lubrication.

The nature and objects of the invention will appear more fully from the accompanying 40 description and drawings and will be particularly pointed out in the claims.

As the invention relates to but one feature of construction in the let-off mechanism, and 45 as the construction and operation of the let-off mechanism are well known and familiar to those skilled in the art, it will be sufficient to illustrate only those parts of a familiar type of mechanism with which the invention 50 is particularly concerned in order fully to

disclose a simple and preferred embodiment of the invention.

In the drawings:

Fig. 1 is a side elevation of the lower rear portion of the side frame of a loom with only 55 those parts shown with which the present invention is concerned.

Fig. 2 is a perspective view of a preferred form of stud.

Fig. 3 is an inside elevation on a larger scale 60 of the upper end of the rocker arm.

Fig. 4 is a view in vertical cross section taken on the line 4—4 of Fig. 3 on a still larger scale and with the stud shown in elevation.

In the construction illustrated, the loom side frame 1 supports one end of the usual lay rocker shaft 2 carrying the lay swords 3. The rocker arm is secured to this rock shaft 2 and is shown as made in two parts, 70 4 and 5, adjustably connected together at 6 according to the usual practice. This rocker arm which thus swings with the lay is connected by a driving rod 7 to a pallet lever 8 fulcrumed at 9 and carrying a pawl 10 cooperating with a ratchet gear, a portion of which is shown at 11, and which controls the operation of the let-off mechanism. There must be a lost motion connection in this type of mechanism between the driving 75 rod and the rocker arm because the rocker arm always swings forward to the same extent and always carries the pawl 10 rearward to the same point, while the forward movement of the pawl 10, or the movement toward 80 the front of the loom, varies.

In the construction illustrated, the driving rod 7 is provided at its forward end with a longitudinally slotted casting 12 secured thereto as by the set screw 13. A headed 90 steel stud is detachably secured in the free or upper end of the rocker arm to cooperate with this slotted casting and a preferred form of stud is shown in Figs. 2 and 4. This stud comprises a large flat head 14, a cylindrical shank 15, a polygonal end 16, herein shown as square, terminating in a screw-threaded section 17. A nut 18 is provided to fit the threaded section 17 and a suitable washer 19 is provided. The polygonal end 100

16 of the stud fits a corresponding polygonal aperture 20 formed in the upper end of the rocker arm 4. The stud is inserted through the longitudinal slot 21 of the casting 12 and then detachably but rigidly secured in the rocker arm by screwing the nut up with the shoulder 22 of the stud shank 15 abutting the outer side of the rocker arm and with the washer 19 abutting the inner side.

10 It will thus be seen that the casting 12 is guided between the rocker arm and the head of the stud and that its slot slides on the shank 15 of the stud. As the stud is made of steel and the casting 12 is usually of iron, these parts operate together with very little wear, even when the casting is not finished and even when no lubrication is provided. Furthermore, when any wear does take place, the stud may be rotarily adjusted by giving 20 it a quarter turn in the arm, thus bringing a fresh surface into sliding engagement with the casting.

15 While the end 16 is shown as square, this is but an example of an equilateral polygon 25 which enables the stud to be rotarily adjusted in any one of a plurality of positions and it is not even necessary, in the broader scope of the invention, that the stud have this polygonal section but the stud is preferably rotarily adjustable in the arm.

20 There is thus provided a very simple and efficient construction for obviating the defects heretofore existing in this mechanism and securing long life to these parts.

25 Having thus described the invention, what is claimed as new, and desired to be secured by Letters Patent, is:

30 1. In a let-off mechanism for looms, a rocker arm having a polygonal aperture in its free end, a pallet lever, a driving rod pivoted at one end to the pallet lever and having a longitudinally slotted casting at the other end, a steel stud having a head, a cylindrical shank and a polygonal end fitting the aperture in the arm, and means for detachably 35 securing the stud in the end of the rocker arm with the casting guided between the arm and the head of the stud and with the slot riding in the shank of the stud.

40 2. In a let-off mechanism for looms, a rocker arm having a polygonal aperture in its free end, a pallet lever, a driving rod pivoted at one end to the pallet lever and having a longitudinally slotted casting at the 45 other end, a steel stud having a head, a cylindrical shank, a polygonal end fitting the aperture in the arm and terminating in a reduced threaded section, and a nut fitting said threaded section and acting detachably 50 to secure the stud in the end of the rocker arm with the casting guided between the arm and the head of the stud and with the slot riding upon the shank of the stud.

55 3. In a let-off mechanism, the construction defined in claim 1, in which the polygonal

aperture in the rocker arm and the polygonal end of the stud are equilateral to enable the stud to be rotarily adjusted in the arm.

60 In testimony whereof, I have signed my name to this specification.
